No. 11,762.

UNITED STATES PATENT OFFICE.

EDMUND STEINLE, OF NEW YORK, N. Y.

DESIGN FOR THE BASE OF A JEWELRY-BOX.

SPECIFICATION forming part of Design No. 11,762, dated May 4, 1880.

Application filed March 25, 1880. Term of patent 3½ years.

To all whom it may concern:

Be it known that I, EDMUND STEINLE, of the city, county, and State of New York, have invented a new and original Design for Base 5 of Jewelry-Box, of which the following is a full, clear, and exact description, reference being had to the accompanying drawings, making part of this specification, in which—

Figure 1 represents a perspective view of 10 my improved base for jewelry-cases, and Fig. 2 a detail vertical transverse section of the same.

Similar letters of reference indicate corresponding parts.

15 This invention relates to an improved design for the bases of jewelry-cases; and it consists of a base for jewelry-cases in which the finishing-cord or trimming is placed upon the base, while the supporting spring-cushion rises 20 directly from the finishing-cord.

Heretofore the bases for jewelry-boxes were recessed, and the supporting spring-cushions secured into the recesses and finished off at their lower parts with a chenille or other cord, 25 which, however, like the cushion, was set into the recess and below the level of the rim of the base. The spring-cushion appeared thereby to be sunk in, and failed to bring out the jewelry sufficiently when the box was opened.

30 The object of my design is to bring out the jewelry in a more effective manner by raising both the finishing-cord and spring-cushion above the base, by which a pyramidal shape, and therefore a more ornamental configura- 35 tion, is imparted to the base.

A in the drawings is the bottom piece, B the finishing chenille or other cord or trimming, and C the spring-cushion, of my improved base for jewelry-cases. The cord B is placed directly upon the bottom piece, A, at such distance from its edge that the top of the case, when brought down upon the base, will inclose the cord, as shown in Fig. 2. The spring-cushion C rises from the level of the cord, so that cord and cushion stand out pyramidal 45 from the bottom piece and bring out the jewelry in a more prominent manner when the case or box is opened. The pyramidal shape of the base renders the same more ornamental and better adapted for the proper artistic exhibition of the articles of jewelry. 50

Having thus described my invention, I claim as new and desire to secure by Letters Patent—

The design for the base of a jewelry box or case, composed of a bottom piece, a finishing-cord placed upon the same, and a cushion extending upward from the level of the cord, substantially as described, and shown in the accompanying illustration. 55

In testimony that I claim the foregoing as my invention I have signed it this 19th day of March, 1880. 60

EDMUND STEINLE.
